UNITED STATES PATENT OFFICE.

ALDEN E. OSBORN, OF NEW YORK, N. Y.

INTERNAL-COMBUSTION ENGINE.

1,419,512.

Specification of Letters Patent. Patented June 13, 1922.

Application filed April 19, 1919. Serial No. 291,418.

To all whom it may concern:

Be it known that I, ALDEN E. OSBORN, a citizen of the United States, and a resident of New York, county and State of New York, have invented certain new and useful Improvements in Internal-Combustion Engines, of which the following is a specification, reference being had to the accompanying drawings, forming a part thereof.

10 This invention relates to improvements in internal combustion engines and its object is to improve the mechanical construction of said engines in order to increase their strength and efficiency. It relates more particularly to engines of the type in which the valve or valves are located within the cylinder and between the side of the piston and the adjacent cylinder wall and the special aim of the invention is to eliminate the side 20 thrust of the piston with the consequent binding action on the valve or valves usually resulting therefrom.

Another object is to provide a construction which will enable the use of a shorter 25 valve or valves and which, by reducing the heating effect on the parts, will permit the use in larger engines than has heretofore been possible of the valve or valves within the cylinder. A still further object is to 30 provide a guide for the part of the piston with which the connecting rod is connected, of such a form as to permit of the use of a long bearing pin so positioned as to be removed from the heat of the combustion 35 chamber. Another object is to so arrange the parts as to provide for more effective lubrication thereof.

These and other objects of the invention will appear in the following specification in 40 which I will describe the invention, the novel features of which will be set forth in appended claims.

Referring to the drawings:

Figure 1 is a sectional elevation of an 45 internal combustion engine which is made according to and embodies this invention.

Figure 2 is a sectional plan view of parts 50 of the same engine illustrating the manner of positioning the sleeves for insertion or removal. The section in this figure is taken on the line 2-2 of Figure 1.

Figure 3 is a sectional plan view on the line 3-3 of Figure 1.

Figure 4 is a sectional elevation of a modified form of this invention applied to an engine having a type of valve mechanism similar in principle of operation to that shown and described in my Patents Nos. 985,198 of Feb. 28, 1911 and 1,279,578 of Sept. 24, 1918.

Figure 5 is a sectional plan view of some of the parts of the engine shown in Figure 4, the section being taken on the line 5-5 of the latter figure.

Figure 6 is a sectional plan view of similar parts to those shown in Figure 5 but illustrating a modified form of construction of these parts.

Figure 7 is a sectional elevation of certain parts of modified construction showing an arrangement for guiding parts of the sleeve 70 actuating mechanism.

Like characters of reference designate corresponding parts in all of the figures of the drawings.

Referring first to the form of engine 75 shown in Figures 1, 2 and 3;

10 designates the cylinder of an internal combustion engine and there are two sleeve valves therein designated by 11 and 12. The casting which forms the cylinder is extended downwardly to form semi-cylindrical guides 13 in alignment with and preferably of the same diameter as the cylinder, and two diametrically opposed pockets 14.

The piston comprises a pressure head 20 85 within the sleeve 12 and of sufficient thickness to carry sealing rings, a guide head 21 within the guides 13 and an intermediate connecting portion 22.

The guide head may have two spaced 90 parts 23 and 24 machined to the diameter of the guides 13, and an intermediate portion 25 of somewhat smaller diameter. The sides thereof adjacent the pockets 14 are extended at 26 to afford a long bearing for the connecting rod pin 27. The connecting rod is designated by 28 and is connected with the crank shaft in the usual manner.

The sleeves 11 and 12 are actuated from a crank shaft 30 with which they are connected by rods 31 and 32 the upper ends of which are pivoted respectively to outwardly extending bifurcated lugs 33 and 34 which when the engine is in condition for operation as in Figure 1, are in parallel relation 105 but which by rotating the sleeves slightly

in opposite directions, may be crossed over each other diagonally as shown in Figure 2, in which case they may be passed through either one of the pockets 14 in assembling 5 the engine or in taking it apart.

Before specifically describing the structures shown in the other figures of the drawings, I will describe the operation and point out some of the advantages of the apparatus 10 illustrated in these first three figures. In the first place the pressure head 20 may be very short as it and the guided head 21 keep it always in axial alinement with the cylinder. Thus the mass of that part of the piston 15 ton which is subjected to the heat of combustion is greatly reduced so that it is easier to keep the piston and the sleeves cool. Then the guides take up all side-thrusts due to the eccentricity of the crank pin and this 20 eliminates side pressure of the piston against the sleeves and of the sleeves against the cylinder walls. This of course reduces the friction of these parts to a much greater extent than is friction added to the machine 25 at the guides 13. Moreover the side thrust of the connecting rod is transferred from inaccessible and more or less delicate parts of the mechanism, to parts which may be more readily reached, and which may be liberally proportioned for performing nothing 30 but this one function. The connecting rod pin 27 may be made longer than the diameter of the piston,—in fact it may be made as long as desired so that a longer and 35 better wearing construction for the connection of the rod 28 with the piston is possible than with formerly known designs. The guides 13 and the connecting rod bearings are removed from the heat of the combustion 40 chamber so that the matter of their lubrication is greatly facilitated. It is also clear that the guide structure does not interfere with putting the sleeves into the cylinder.

45 In the engine shown in Figures 4 and 5 the guides 13^A are integral parts of a separate member 15 which is secured between the casting which forms the engine cylinder 10^A and the base 16, and are of smaller diameter, 50 as is of course the guided part 21^A of the piston. So too are the pockets 14^A smaller, as in this case the sleeve 17 does not have to pass between the guides or through the pockets. This construction has the advantages 55 of the construction of Figures 1-3 and the additional advantage that it permits the renewal of the guide surfaces without replacing the cylinder. This separation of the guide from the cylinder also enables 60 these two parts being made of different materials, best suited for these special purposes. Also the pressure head of the piston and the valve parts can be separated from the base of the engine.

65 In this case the sleeve actuating shaft 30

is shown below the member 15 and the rod 35 which connects it with the sleeve 17 passes through an opening in this member. If it is desired, a housing 18 may be added to prevent this opening from furnishing a 70 communicating passage between the spaces above and below the member 15.

If it is desired to very completely separate the parts above and below the guide member, the construction shown in Figure 6 may 75 be used. Here the part of the member which forms the guide is cylindrical as shown at 13^B, and so is the guide head 21^B which fits it.

Figure 7 shows an arrangement for furnishing a guide between the sleeve actuating shaft 30 and the sleeve 17. The member 15^A is constructed as before to form the guides 13^A but is further constructed to form parallel therewith, other guides 19. A rod 80 36 connected with the sleeve has an enlargement 37 which runs in these guides and which is connected by a rod 38 with shaft 30.

This invention may be used with other types of engines than those shown and described. While it is my present belief that its greatest advantage is with engines of sleeve valve types it is obviously of similar advantage with such engines as those in which the valve forms a part of the wall of 90 the cylinder or is a crescent shaped segment bearing upon the pressure head of the piston or the rings thereof and within the cylinder wall. It is possible to make many variations and modifications of construction 95 without departing from the scope and spirit of this invention, and I intend no limitations other than those imposed by the appended claims.

What I claim is:

1. An internal combustion engine comprising a crank-shaft, a piston having a pressure head, a movable valve member over which said pressure head reciprocates, said piston having a guide head and an intermediate portion spacing said guide head from the pressure head, spaced stationary guides for the guide head having a pocket therebetween, a connecting rod pin operating in said pocket and a connecting rod on said pin 110 and connected with the crank-shaft.

2. An internal combustion engine comprising a crank-shaft and a piston having a pressure head, a movable valve member over which said pressure head reciprocates, said piston having a guide head and an intermediate portion spacing said guide head from the pressure head, spaced stationary guides for the guide head, said guide head fitting between said guides, and having parts at an 120 angle to the guides wider than the space between the guides, a connecting rod pin through the wider part of the guide head, and a connecting rod on said pin and connected with the crank-shaft.

3. An internal combustion engine comprising a crank-shaft, a piston having a pressure head, a cylinder in which said pressure head reciprocates, said piston having a 5 guide head with opposed semi-cylindrical surfaces, a transversely wider part between said surfaces and an intermediate portion between the pressure head and the guide head, a stationary guide member having 10 semi-cylindrical guide surfaces and constructed to form opposed pockets between the guide surfaces, a connecting rod pin through the wider part of the guide head extending beyond the radii of the semi-cylindrical guide surfaces and a connecting rod 15 on said pin and connected with the crank-shaft.
4. An internal combustion engine comprising a crank-shaft and a piston having a 20 pressure head, a movable valve member over which said pressure head reciprocates, said piston having a guide head with opposed semi-cylindrical surfaces, a transversely wider part between said surfaces, and an 25 intermediate portion between the pressure head and the guide head, a stationary guide member having semi-cylindrical guide surfaces, and constructed to form opposed pockets between the guide surfaces, a connecting 30 rod pin through the wider part of the guide head, and a connecting rod on said pin and connected with the crank-shaft.
5. An internal combustion engine comprising a crank-shaft and a piston having a 35 pressure head, a movable valve member over which said pressure head reciprocates, said piston having a guide head with opposed semi-cylindrical surfaces, a transversely wider part between said surfaces, and an 40 intermediate portion between the pressure head and the guide head, a stationary guide member having semi-cylindrical guide surfaces, a connecting rod pin through the wider part of the guide head, and a connecting rod on said pin and connected with the crank-shaft, and constructed to form opposed 45 pockets between the guide surfaces.
6. An internal combustion engine comprising a crank-shaft and a piston having a 50 pressure head, a movable sleeve valve within which said pressure head reciprocates, said sleeve valve having an outwardly projecting lug, said piston having a guide head with opposed semi-cylindrical surfaces of 55 substantially the same diameter as that of the outside of the sleeve valve, a transversely wider part between said surfaces, and an intermediate portion between the pressure head and the guide head, a stationary 60 guide member having semi-cylindrical guide surfaces and constructed to form opposed pockets between the guide surfaces to form clearance spaces for the wider part of the guide head and for the sleeve valve lug, a connecting rod pin through the wider 65 lug, a connecting rod pin through the wider
- part of the guide head, and a connecting rod on said pin and connected with the crank-shaft.
7. An internal combustion engine comprising a crank-shaft and a piston having a 70 pressure head, a movable sleeve within which said pressure head reciprocates, said sleeve valve having an outwardly projecting lug, said piston having a guide head with opposed semi-cylindrical surfaces of 75 substantially the same diameter as that of the outside of the sleeve valve, a transversely wider part between said surfaces, and an intermediate portion between the pressure head and the guide head, a stationary guide member having semi-cylindrical guide surfaces and constructed to 80 form opposed pockets between the guide surfaces to form clearance spaces for the wider part of the guide head and for the 85 sleeve valve lug, a connecting rod pin through the wider part of the guide head, and a connecting rod on said pin and connected with the crank-shaft, said guide member and guide head being arranged to separate the parts of the engine above and below the guide member.
8. An internal combustion engine comprising a crank-shaft, a cylinder, a piston having a pressure head, a movable valve 95 member within the cylinder against which said pressure head reciprocates, said valve member having an outwardly projecting lug, said piston having a guide head of as large diameter as the outside of the valve 100 member, a stationary guide member for the guide head constructed with a pocket therein providing clearance for the valve lug when the valve member is inserted through the guide into the cylinder, a connecting 105 rod pin in the guide head and a connecting rod on said pin and engaged with the crank-shaft.
9. In an internal combustion engine, an operating cylinder and a relatively stationary guide, a piston having a pressure head operating within the cylinder and a guide head spaced from the pressure head and operating within the guide, a relatively short valve member operating in the cylinder between the pressure head and cylinder wall and entirely above or beyond the guide head of the piston, a crank-shaft and a connecting rod connected between the guide head and said crank-shaft.
10. An internal combustion engine comprising a crank-shaft and a piston having a pressure head, a cylinder in which said pressure head reciprocates, said piston having a guide head with opposed semi-cylindrical surfaces, a transversely wider part between said surfaces, and an intermediate portion between the pressure head and the guide head, a stationary guide member having semi-cylindrical guide surfaces, and 125
- 110
- 115
- 120
- 125
- 130

constructed to form opposed pockets between the guide surfaces, a connecting rod pin through the wider part of the guide head extending beyond the radius of the 5 semi-cylindrical guide surfaces, and a connecting rod on said pin and connected with the crank-shaft.

11. An internal combustion engine comprising a crank-shaft and a piston having 10 a pressure head, a movable valve member against which said pressure head reciprocates, said valve member having an outwardly projecting lug, said piston having a guide head of substantially the same diameter 15 as that of the outside of the valve member, an intermediate portion between the pressure head and the guide head, a stationary guide member having a semi-cylindrical guide surface constructed with 20 a pocket therein to form a clearance space for the sleeve lug to pass through in assembling the parts, a connecting rod pin through the guide head, and a connecting rod on said pin and connected with the 25 crank-shaft.

12. An internal combustion engine, comprising a crank shaft, a cylinder, movable valve means, within said cylinder, a piston having a pressure head reciprocating within said movable valve means, said piston 30 having a guide head spaced from the pressure head, and of greater diameter than said pressure head, and the cylinder having a guide extension substantially equal in diameter to that part of the cylinder within 35 which the valve means operates, said guide extension receiving the guide head of the piston, and being located beyond the valve means, said valve means operating in the cylinder above the guide extension, and being of a thickness to compensate for the difference in diameter between the pressure head, and the guide head of the piston, and a connecting rod pivotally engaged with the guide head, and with the crank 40 shaft.

In witness whereof I have hereunto set my hand this 10th day of April, 1919.

ALDEN E. OSBORN.
